UNITED STATES PATENT OFFICE.

JENS NIELSEN, OF CEDAR FALLS, IOWA.

ROTARY ENGINE OR PUMP.

1,105,449.

Specification of Letters Patent. Patented July 28, 1914.

Application filed December 17, 1912. Serial No. 737,347.

To all whom it may concern:

Be it known that I, JENS NIELSEN, a citizen of the United States, residing at Cedar Falls, in the county of Blackhawk and State 5 of Iowa, have invented certain new and useful Improvements in Rotary Engines or Pumps, of which the following is a specification.

This invention has relation to rotary engines or pumps especially adapted to be positioned vertically when in operation although the machine may be placed in other positions if desired.

An object of the invention is to provide 10 an engine or pump comprising a casing with a single rotor mounted therein, the parts being so arranged that the weight of the water from above and the resistance of the water from below will have a tendency to 15 counterbalance the rotor in its position in the casing whereby the tendency to longitudinal movement on the part of the rotor is 20 eliminated.

Another object of the invention is to provide 25 an engine or pump comprising a casing having openings at its upper and lower ends and provided upon its inner side with teeth of peculiar configuration. A rotor is journaled in the casing and is provided with a 30 pocket in which is journaled a piston having teeth of peculiar configuration which mesh with the teeth provided upon the casing. A cylinder surrounds the casing and is spaced from the same, and communicates 35 with the openings at the lower end of the casing. This space between the cylinder and the casing constitutes a fluid passageway. Plates are fixed to the ends of the 40 rotor and fit snugly in the end portions of the casing. These plates are provided with ports which communicate at their inner ends with the pocket in the rotor. These ports are out of alinement with each other longitudinal of the piston and one port is located 45 at one side of the axis of the piston while the other port is located at the opposite side of the axis of the piston. A head is provided at one end of the casing and is fixed with relation to the casing and supports a 50 ring which engages the cylinder. A pipe is connected at one end with the ring and surrounds a shaft which is adapted to operate the rotor.

With these and other objects in view, the 55 invention consists in certain novel features

of construction as hereinafter shown and described, and then particularly pointed out in the claims and in the drawings illustrative of the preferred embodiment of the invention, Figure 1 is a vertical sectional view of the engine or pump. Fig. 2 is a transverse sectional view of the same cut on the line 2—2 of Fig. 1. Fig. 3 is a similar view cut on the line 3—3 of Fig. 1. Fig. 4 is a similar view cut on the line 4—4 of Fig. 1. Fig. 5 is a similar view cut on the line 5—5 of Fig. 1. Fig. 6 is a similar view cut on the line 6—6 of Fig. 1.

Corresponding and like parts are referred to in the following description and indicated in all the views of the accompanying drawings by the same reference characters.

The engine or pump comprises a cylindrical casing 1 which is provided upon its inner side with teeth 2. These teeth are of greatest transverse thickness at their bases or roots and gradually diminish in transverse thickness toward their inner ends as best shown in Fig. 2 of the drawing. The inner 75 side of the casing 1 at the bottoms of the spaces between the teeth 2 is provided with concavities 3 which extend the full length of the teeth 2.

The casing 1 is provided at its upper end 80 portion with openings 4 and at its lower end portion with openings 5. These openings may be of any desired number or any appropriate shape or configuration.

A shaft 6 enters the upper portion of the casing 1 and is provided at its lower end with a plate 7 which in turn is provided with a port 8, a rotor 9 is fixed to the plate 7 and is provided with a peripheral pocket 10. A plate 11 is secured to the lower end 90 of the rotor 9 and is provided with a port 12. The ports 8 and 12 communicate at their inner ends with the pocket 10 but the said ports are out of alinement with each other longitudinal of the pocket. The plates 100 7 and 11 are preferably held in position with relation to the rotor 9 by means of bolts 13. A shaft 14 is supported at its ends in the plates 7 and 11 and traverse the length of the pocket 10. The said shaft 14 is centrally positioned with relation to the pocket. A piston 15 is journaled upon the shaft 14 and is provided with peripheral teeth 16. These teeth are less in transverse thickness near their inner ends than at their 110

outer ends as best shown in Fig. 2 of the drawing and the teeth 16 are adapted to mesh with the teeth 2 in the casing 1. The port 8 in the plate 7 is located at one side 5 of the axis of the shaft 14 while the port 12 in the plate 11 is located at the opposite side of the said axis. The plate 11 is journaled upon a pin 17 which is supported in the head 18. The head 18 is provided upon its upper 10 side with an annular flange 19 which fits snugly in the lower end of the casing 1 as best shown in Fig. 1 of the drawing. A cylinder 20 surrounds the casing 1 and is connected at its lower end with the head 18. 15 The inner side of the cylinder 20 is spaced from the outer side of the casing 1 and this space constitutes a liquid passage-way.

A head 21 is mounted upon the upper end of the casing 1 and the shaft 6 is journaled 20 in the said head 21. The openings 4 are located between the head 21 and the plates 7 as best shown in Fig. 1. A ring 22 is connected to the upper end of the cylinder 20 and its inner side is spaced from the outer 25 or upper side of the head 21. A pipe 23 is connected at its lower end with the ring 22 and surrounds the shaft 6 and is spaced from the same. Screws 24 pass through the ring 22 and also pass through the head 21 and enter the upper end portion of the casing 1. Bushings 25 are located upon the intermediate portions of the said screws 24 and serve as means for holding the ring 22 in proper spaced relation from the head 21.

In operation the casing 20 is wholly submerged below the surface of the liquid which is to be operated upon. When the shaft 5 is rotated in one direction the rotor 9 is carried around with the same and the 40 liquid flows into the casing 1 through the openings 4. The liquid then flows down through the port 8 in the plate 7 and is encountered by the teeth 16 of the rotor 15 and is forced in a downward direction through 45 the port 12 in the plate. Thence the liquid is forced out of the casing 1 through the openings 5 and up through the space between the cylinder 20 and the casing 1, thence through the space between the ring 50 22 and the head 21 and then up through the pipe 23.

In view of the fact that the casing 1 is provided at its inner side and at the bottoms of the spaces between the teeth 2 with 55 the concavities 3, the said concavities will receive a certain amount of the liquid when the teeth 16 encounter the teeth 2. This is just sufficient to prevent this liquid from being trapped between the intermeshing 60 teeth and thus the pump will operate in a noiseless manner and the knocking or pounding due to what is generally termed a water hammer is avoided. In forcing the water down through the casing, the weight 65 of the water pushing the rotor in an upward

direction will counterbalance the weight of the rotor and the parts to which it is attached and which are carried by the same.

It will be readily appreciated that in the construction of the machine, the various parts shown and described as integral may be made in separate sections and joined together and that parts, shown separate may be made in integral units and assembled as herein before described. 75

The operation of the machine when used as an engine is as follows: The fluid enters the pipe surrounding the shaft and follows the passage-way between the cylinder and the casing down and in through openings 5 80 under the rotor, up through rotor and casing and out at openings 4.

A head in which the shaft is journaled and packed, may be supposed to close the pipe up above and a suitable inlet provided 85 into the pipe below said head for the fluid to enter the pipe.

Having described the invention what is claimed, is:—

1. A pump comprising a casing, a rotor 90 journaled in the casing and including spaced plates having ports, a cylinder surrounding the casing and spaced from the same, a head located at one end of the cylinder and closing the same and spaced from the adjacent 95 ported plate, said casing having a liquid passage-way leading into the cylinder and located between the last mentioned plate and head.

2. A pump comprising a casing, a rotor 100 journaled in the casing, a cylinder surrounding the casing and spaced from the same and closed at one end, said casing having passageways located below the rotors which communicate with the interior of the cylinder, said cylinder being provided with an outlet located above the rotor and having a port leading through its side into the casing 105 at a point above the rotor.

3. A pump comprising a casing provided 110 upon its inner side with teeth, a rotor journaled in the casing, a piston journaled in the rotor and having peripheral teeth adapted to mesh with the teeth in the casing, the spaces between the teeth in the casing being 115 deeper radially than the lengths of the teeth upon the piston.

4. A pump comprising a casing provided 120 upon its periphery with interiorly arranged teeth, and at its opposite ends with counterbores, rotatable plates having slightly greater diameters than the inner diameter of the casing and rotatably mounted in the counterbores and having ports formed adjacent their peripheries with their outer walls 125 flush with the inner periphery of the casing, a rotor arranged between the plates and connected therewith, a rotatable toothed piston arranged between the rotatable plates and connected therewith to co-operate with the 130

teeth of the casing, a cylinder surrounding the casing in spaced relation to form a passage employed solely for the discharge of the liquid in an upward direction, and a 5 member arranged in the upper end of the casing for closing the upper end thereof above the upper plate.

5. A pump, comprising a casing, rotatable plates mounted within the opposite ends of 10 the casing, and provided adjacent their peripheries with ports having their outer walls flush with the inner periphery of the casing, a rotor arranged between the plates and connected therewith, a rotatable piston arranged 15 to one side of the rotor and connected with the plates, a cylinder surrounding the casing in spaced relation to provide an outlet passage for the liquid, and means arranged adjacent the upper end of the casing to separate the same from the outlet passage.

6. A pump comprising a substantially vertical casing provided with interiorly arranged teeth, rotatable plates arranged within the casing near the upper and lower 25 ends thereof, a rotor arranged between the plates and connected therewith, a relatively rotatable piston provided with teeth to engage with the casing teeth and adapted to force a liquid downwardly continuously, 30 said rotatable plates being provided with ports, and a cylinder surrounding the casing in spaced relation to provide a liquid outlet passage through which the discharge liquid passes continuously in an upwardly direction.

7. A pump of the character described comprising a substantially vertical casing provided with interiorly arranged teeth, plates rotatably mounted within the opposite 40 end portions of the casing and extending radially beyond the bases of the teeth and having ports with their outer walls substantially flush with the inner periphery of the casing, a rotor mounted between the plates and connected therewith, and a rotatable toothed piston rotatably mounted between the plates to coöperate with the casing teeth.

8. A pump of the character described, comprising a substantially vertical casing 50 provided with internally arranged teeth,

plates rotatably mounted within the opposite ends of the casing and extending radially outwardly beyond the bases of the teeth, and having ports with their outer walls arranged substantially flush with the inner 55 periphery of the casing, a rotor mounted between the plates, rods extending through the two plates for radially connecting the rotor therewith, a toothed rotatable piston arranged between the plates upon one side of 60 the rotor to coöperate with the casing teeth, and a shaft carrying the rotatable piston with its opposite ends journaled through the two plates.

9. A pump of the character described 65 comprising an upstanding casing provided with interiorly arranged teeth which decrease toward their free ends, plates rotatably mounted in the opposite ends of the casing and extending radially outwardly beyond the base of the teeth and having ports with their outer walls substantially flush with the inner periphery of the casing, a rotatable piston arranged between and carried by the plates and having teeth to coöperate 70 with the casing teeth which increase in width outwardly, a rotor arranged to one side of the rotatable piston and connected with the plates, and a cylinder surrounding the casing in spaced relation thereto.

10. A pump of the character described, comprising an upstanding casing, rotatable plates mounted in the opposite ends thereof and provided with ports having their outer walls substantially flush with the inner surface of the casing, said ports being out of longitudinal alinement with each other, a rotatable piston mounted between the plates and carried thereby, a rotor mounted between the plates, carried thereby, and arranged upon one side of the piston, and a cylinder surrounding the casing in spaced relation thereto.

In testimony whereof I affix my signature in presence of two witnesses.
